UNITED STATES PATENT OFFICE.

LOUIS C. UPTON, OF ST. JOSEPH, MICHIGAN, ASSIGNOR TO UPTON MACHINE COMPANY,
OF ST. JOSEPH, MICHIGAN, A CORPORATION OF MICHIGAN.

DESIGN FOR A CABINET FOR A WASHING MACHINE.

60,481.

Specification for Design.

Patented Feb. 21, 1922.

Application filed March 24, 1920. Serial No. 368,427. Term of patent 7 years.

To all whom it may concern:

Be it known that I, LOUIS C. UPTON, a citizen of the United States, residing at St. Joseph, in the county of Berrien and State of Michigan, have invented a new, original, and ornamental Design for a Cabinet for Washing Machines, of which the following is a specification, reference being had to the accompanying drawing, forming a part thereof.

Fig. 1 is a perspective view showing the front and one side of the cabinet.

Fig. 2 is a similar view showing the rear and the same side of the cabinet.

What I claim and desire to secure by Letters Patent is:—

The ornamental design for a cabinet for a washing machine, as shown.

Signed at St. Joseph, in the county of Berrien and State of Michigan, this 19th day of March, A. D. 1920.

LOUIS C. UPTON.
